 Letters Patent No. 2243-Dated Jan'y. 16. 1866.
 Design for a Trade-mark for Pens and Pen Boxes.

The schedule referred to in these Letters Patent and making part of the same.

To all whom it may concern:

Be it known that I, John B. Maring, of the City of New York, in the County and State of New York, have originated a new and ornamental design for a Trade-mark for Pens and Pen Boxes for Pens; and I do hereby declare that the following is a full and exact description thereof, reference being had to the accompanying drawing and to the letters of reference marked thereon, in red.

The drawing is a front or face view of a pen having my trade-mark embossed or otherwise made distinctly visible thereon. The same trade-mark serves by being printed, embossed, branded, or otherwise produced on pen boxes. At the points indicated by l, l, etc. in red, appears a profile portrait of the head, and at the points marked m, m, etc. in red, appear the shoulders of Honorable Salmon P. Chase, late Secretary of the Treasury, and the present Chief Justice of the Supreme Court of the United States. Words, marks, etc. not interfering with this design may be added at will.

This design for trade mark is intended to form a distinctive mark by which it may be recognized or described in the trade.

What I claim as my invention and desire to secure by Letters Patent is the design for a trade mark composed of the Profile Portrait of the Honorable Salmon P. Chase, as hereinafter set forth.

 Jas. Maring.
